[57] CLAIM

The ornamental design for an arcade game cabinet, as shown and described.

DESCRIPTION

FIG. 1 is a perspective view of the arcade game cabinet showing our new design.

FIG. 2 is a side view of the arcade game cabinet, with the opposite side being essentially the same.

FIG. 3 is a front view of the arcade game cabinet.

FIG. 4 is a rear view of the arcade game cabinet.

FIG. 5 is a top view of the arcade game cabinet.

FIG. 6 is a bottom view of the arcade game cabinet.
